UNITED STATES PATENT OFFICE

1,979,957

SLICING MACHINE

William J. Campbell, Indianapolis, Ind., assignor
to American Slicing Machine Company, Chi-
cago, Ill., a corporation of New York

Original application September 16, 1932, Serial
No. 633,522. Divided and this application April
27, 1933, Serial No. 668,161

5 Claims. (Cl. 308—163)

My invention relates to an improvement in slicing machines and has for one purpose the provision of improved bearing means for knife and knife shaft. Another object is the provision of improved means for assembling or disassembling, knife, knife shaft, and knife pulley. Another object is to obtain a bearing that is noiseless, having far less noise than the conventional roller or ball bearing. Another object is the provision of a bearing in which spring tension is provided to take up all lost motion and end play which might be caused by inaccuracy in manufacture. Another object is the provision of means herein shown as spring tension means, which automatically take up what little wear there is in the bearings due to end play. Another object is the provision of a bearing assembly that can be assembled and disassembled without the aid of any tools.

Other objects will appear from time to time in the course of the specification and claims.

The present application is a division of application Serial No. 633,522, filed on September 16, 1932, which application is itself a continuation in part of application Serial No. 598,131, filed on March 11, 1932.

I illustrate my invention more or less diagrammatically in the accompanying drawings, wherein—

Figure 1 is an end elevation;
Figure 2 is a vertical axial section along the knife shaft;
Figure 3 is a section on the line 3—3 of Figure 2;
Figure 4 is a partial section;
Figure 5 is a section similar to Figure 2 through a slightly variant form of device;
Figure 6 is a section through a further variation; and
Figure 7 is a section through a still further slight variation.

Like parts are indicated by like symbols throughout the specification and drawings.

Referring to the drawings, A generally indicates any suitable base with anti-vibrational pads or supports A¹ which may rest upon any suitable supporting surface A² which may be a counter or the like.

B indicates a motor housing mounted on the base A. It will be understood that within it is any suitable motor and motor shaft not herein indicated, with a suitable motor pulley about which may pass any suitable belt B³.

C indicates any suitable housing extension projecting upwardly from the base A. Formed integrally with it is a flared sleeve C¹ terminating

rearwardly in a generally cylindrical portion C². The cylindrical portion C² is shown as including an inwardly extending sleeve C³ which may be mounted upon or strengthened by fins or connecting webs C⁴. Positioned within the sleeve C³, at opposite ends thereof, are bearing sleeves proper C⁵, flanged at each end as at C⁶, these bearing sleeves being thrust inwardly into opposite ends of the surrounding sleeve C³. They may each be grooved as at C⁷ to provide oil passages whereby oil or any other suitable lubricant delivered downwardly from the cup C⁸ may reach the bearing surface of the sleeves C⁵ and flanges C⁶.

D indicates a knife shaft in bearing engagement with each of the said sleeves C⁵. It is enlarged at one end as at D¹, this enlargement abutting against the flange C⁶ of one of the sleeves C⁵, as shown in Figure 2. The knife shaft is reduced at its outer end as at D³ which reduced end terminates in a species of button D⁴ slotted or channelled at the sides as at D⁵ to receive any suitable securing washer D⁶ which is slotted at one side as at D⁷ to permit it to be slipped on the button D⁵. Surrounding the reduced portion D³ is the compression member D⁸ with an enlarged flange D⁹ adapted to abut against the flange C⁶ of the nearest bearing sleeve C⁵. Associated with the compression member D⁸ but slidably in relation thereto, is the locking cup D¹⁰ which surrounds the washer D⁶. D¹¹ is any suitable spring compressed between the cup D¹⁰ and the flange D⁹, whereby the cup is urged against the washer D⁶ and the member D⁸ with its flange D⁹ is urged against the shoulder in the knife shaft D and against the flange C⁶ of the bearing sleeve C⁵. D¹² is any suitable means for preventing relative rotation of the knife shaft D and the compression member D⁸. It is shown herein as a pin D¹² penetrating apertures D¹⁴ in the two members.

E is any suitable outer cap or closure, mounted on the end of the sleeve C¹ and closing the parts last described. E¹ is a gasket or sealing member.

Referring to the structure shown in Figure 2 the disc D¹⁵ which may be press-fitted on the shaft D has secured to a rear face thereof an inner pulley cup G and an outer pulley cup G¹, each cup being formed with a flat inner web portion G², these inner web portions abutting against each other and being secured as by a clamp ring G³, and by the screws G⁴, to the enlarged member D¹ of the shaft D. D¹⁶ is a shoulder on the member D¹ against which are clamped, as illustrated in Figures 5 and 7, the web portions of the cups G, G¹ by the disc D¹⁵, which may be press-fitted. G⁵ is any suitable rotary knife secured to the shaft D

as by the screw G^6 . The details of the knife do not of themselves form part of the present invention, but it is noted that the knife is forwardly recessed as at G^7 . Note that the pulley assembly 5 is housed within the flared sleeve C^1 , the front of this flared sleeve being closed by the knife G^5 itself.

H generally indicates any suitable work supporting carriage the details of which do not form 10 part of the present invention. It may be mounted upon tracks H^1 for manual reciprocation and may be provided with a pusher plate H^2 . H^3 is a gauge plate which may be controlled for example as by the adjusting handle H^4 , through any suitable intermediate mechanism. H^5 is any suitable slice receiver.

Referring to the form of Figure 5 I illustrate an outer removable sleeve J in which may be positioned the actual bearing sleeves J^1 with their 20 flanges J^2 . Positioned about the outer end of the knife shaft D is a thrust member J^3 which is held against rotation in relation to the knife shaft D and may be moved longitudinally therealong. I illustrate for example an axially extending 25 groove J^4 in the knife shaft penetrated by a pin J^5 inwardly projecting from the wall of the sleeve J^3 . The end of the knife shaft terminates in a screwthreaded portion J^6 upon which is mounted the nut J^7 , the lock washer J^8 and the lock nut J^9 . The thrust member or collar J^3 is moved, in response 30 to the rotation of the nut J^7 , against the flange J^2 of one of the bearing sleeves J^1 . The enlargement D^1 of the opposite end of the knife shaft engages the face of the opposed flange J^2 35 and the thrust member J^3 engages the face of the opposite flange J^2 . By interposing the thrust member J^3 between the nut J^7 and one of the flanges J^2 I obtain an exceedingly accurate and true opposition of the thrust member J^3 to the flange J^2 , as the member J^3 is aligned by the shaft 40 and is therefore independent of imperfections in the accuracy of the screwthreading of the nut J^7 and the opposed portion of the shaft. In other words, the member J^3 is a self-aligning thrust member which obtains a true and accurate surface engagement against the flange J^2 .

In the form of Figure 6 I illustrate a somewhat different means for maintaining the proper tightness of the knife and pulley assembly. In the 50 place of the thrust member J^3 I provide a similar thrust collar L . Associated with it is a collar L^1 which may be pinned as by the pin L^2 to the shaft D , whereby there is no relative movement of the collar L^1 in relation to the shaft D . The collar is 55 flanged as at L^3 and provided with a generally cylindrical portion L^4 of less diameter than the flange. The flange L^3 is shown as of about the same diameter as the collar L . Compressed between the flange L^3 and the collar L is a spring L^5 60 which thrusts the collar L against the opposed flange J^2 of the bearing sleeve J^1 . In order to prevent rotation of the collar L in relation to the shaft D , while permitting axial movement, I illustrate, as an example, a pin L^6 interpenetrating 65 both with the collar L and the fixed collar L^1 .

Referring to the form of Figure 7, I dispense with the sleeve J , returning to the form shown in Figures 1 and 2, with the sleeve C^3 integral with the frame of the device. Referring to the figure, 70 M^1 is any suitable oiling duct controlled by any suitable oiler M^2 . The shaft assembly is held together much as in the case of Figure 2, that is to say, a thrust member D^8 is held against rotation relative to the shaft by the pin D^{12} and it is 75 axially urged into position as by the spring D^{11} .

In the place of the abutment member D^{10} and the lock washer D^6 of Figure 1, I employ a screw O^5 with an abutment washer O^6 for engagement with the spring D^{11} .

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

The structure herein described and shown forms a light, easily operated and efficient slicing machine of the manual feed type, in which the rotary knife is rotated at relatively high speed by electric motor means. The carriage H is manually moved across the face of and past the cutting edge of the knife. The slices engaged by the gauge plate H^3 are received on the slice receiving member H^5 .

I provide simple and improved bearing means 100 for the knife shaft D . It is to the highest degree important that the knife rotate smoothly, with a minimum of friction and therefore of a minimum of wear and of lost power. I employ the bearing sleeves C^6 or J^1 which may be of any suitable 105 material, but I find, as a practical material, a mixture of bronze, lead and graphite. However, I do not rely on the nature of the material itself alone, but provide means for injecting a lubricant into the space about the central portion of the 110 shaft D , namely the duct or oiling member C^8 or M^2 .

In order to insure a close and accurate engagement of the opposed bearing faces I provide thrust collars or members, such as the member D^8 of 115 Figures 1, 2 and 4, with spring means for urging the opposed portion of the collar against the opposed flange C^6 of the bearing sleeve C^6 . I have shown in my various figures a variety of means for obtaining this result. I find the form 120 of Figures 1 and 2 particularly practical as admitting of a quick and ready method of assembling and disassembling the device. Assume that the parts are in the position shown in Figures 1 and 2 and that the user wishes to disassemble 125 the knife unit. He first unscrews the cap E . He then thrusts the locking cup D^{10} from the position in which it is shown in Figure 2 into the position in which it is shown in Figure 4, thrusting it against the spring D^{11} and compressing the 130 spring. This moves the cup out of alignment with the washer D^6 , which can then be slipped out of place by means of its slot D^7 . There is then nothing to prevent the entire knife assembly, including the knife itself, the pulley, and the knife 135 shaft, right out of the bearing sleeves. The compression of the spring D^{11} prevents this from happening accidentally, since it always holds the locking disc or cup D^{10} in alignment with or about the washer D^6 , whereby the washer cannot be 140 slipped accidentally out of place.

If the operator wishes to remove the knife from the rest of the assembly he can do so, by loosening the screw G^6 . Thus I have provided a bearing which can be assembled and disassembled 145 without the aid of any tools.

The spring tension means, for example the spring D^{11} of Figure 4 or the spring L^5 of Figure 6, such spring means shown in all form except Figure 5, is effective to take up all lost motion 150

- and end play which might be caused by inaccuracy in manufacture. This spring tension further automatically takes up what little wear there may be in the bearings due to end play.
- 5 In cutting meat the pressure at the side of the knife is from right to left, referring to the parts in the position in which they are shown in Figure 1. This pressure on the knife shaft is in the same direction as the spring which normally 10 tends to pull the knife shaft. The bearing so provided is noiseless.
- I claim:
1. In combination, a base, a bearing sleeve assembly normally fixed on said base, a knife shaft rotatable in said assembly, means for holding said knife shaft against axial movement in relation to said bearing sleeve assembly including an integral thrust shoulder on the shaft adjacent one end thereof and means at the opposite end of the 20 shaft for resiliently mounting the thrust shoulder in contact with the bearing sleeve assembly, an enlargement at one end of said knife shaft beyond said thrust shoulder, a knife secured to the forward face of said enlargement, and a pulley structure secured to the rear face of said enlargement.
  2. In combination, a base, a bearing sleeve assembly normally fixed on said base, a knife shaft rotatable in said assembly, means for holding 30 said knife shaft against axial movement in relation to said bearing sleeve assembly including an integral thrust shoulder on the shaft adjacent one end thereof and means at the opposite end of the shaft for resiliently mounting the thrust shoulder in contact with the bearing sleeve assembly, an enlargement at one end of said knife shaft beyond said thrust shoulder, a knife secured to the forward face of said enlargement, a pulley structure secured to the rear face of said enlargement, said pulley structure including a plurality of mating cups having edge portions flared apart and means passing through said enlargement from the forward face thereof to secure the pulley to the rear face thereof, said knife being cut 40 away adjacent said securing means whereby to provide ready access thereto.
  3. In combination, a shaft and means for rotating it, an outer sleeve surrounding said shaft, a plurality of closed bearing sleeves mounted one 50 at each end of the outer sleeve, each such bearing sleeve having cylindrical exterior and interior surfaces, and being provided with a flange adapted to engage the end of the outer sleeve and limit the penetration of said bearing sleeve within said outer sleeve, an enlargement on one end of said knife shaft adapted to engage one of said flanges, a thrust member axially movable in relation to the other end of said shaft and yielding means for thrusting it against the opposite of said flanges, including an abutment on the shaft, and a coil spring surrounding the shaft and compressed between the thrust ring and the abutment.
  4. In combination, a shaft and means for rotating it, an outer sleeve surrounding said shaft, a plurality of bearing sleeves mounted one at each end of said outer sleeve, an enlargement on one end of said shaft adapted to engage an end of one of said sleeves, the opposite end of the shaft adjacent the outer end of the other sleeve being reduced in diameter to thereby define an annular shoulder positioned slightly inwardly of the outer end of said sleeve, a thrust member mounted upon said reduced portion of the shaft and axially movable in relation to said shaft, and yielding means for thrusting it against the outer end of said other sleeve, said thrust member and said shoulder being provided with longitudinally aligned recesses and a connecting pin engaged in said recesses to thereby lock the thrust member against rotation relative to the shaft.
  5. In combination, a shaft and means for rotating it, an outer sleeve surrounding said shaft, a plurality of bearing sleeves mounted one at each end of said outer sleeve, an enlargement on one end of said shaft adapted to engage an end of one of said sleeves, a thrust member axially movable in relation to the other end of said shaft, and yielding means for thrusting it against an end of the opposite of said sleeves, including a laterally removable washer interpenetrating with one 110 end of the knife shaft, a locking cup adapted, when in washer engaging position, to prevent lateral movement of the washer, and spring means compressed between said locking cup and said thrust member, the knife shaft being provided 115 with a button for engagement with said washer and a neck therefor, the washer being provided with a slot of sufficient diameter to permit the washer to be slipped on the neck of said button.
